UNITED STATES PATENT OFFICE.

HENRY ADLER, OF ALLEGHENY, PENNSYLVANIA.

DESIGN FOR AN OVEN.

SPECIFICATION forming part of Design No. 31,906, dated November 28, 1899.

Application filed June 7, 1899. Serial No. 719,718. Term of patent 14 years.

To all whom it may concern:

Be it known that I, HENRY ADLER, a citizen of the United States, residing at Allegheny, State of Pennsylvania, have invented a new 5 and useful Design for Ovens, of which the following is a specification, reference being had to the accompanying drawing.

In the drawing forming part of this specification a perspective view of an oven embodying my design is shown.

The leading feature of the design consists in an oven of the configuration illustrated in the drawing, having its exterior surface ornamented, as shown.

15 As shown in the drawing, 1 is the oven,

which is formed of the shape shown and is provided with the door 2. The sides of the oven and the door are provided with the ornaments 3.

I claim—

20 The design for an oven as shown and described.

In testimony whereof I have hereunto set my hand, at Pittsburg, county of Allegheny, and State of Pennsylvania, this 29th day of 25 May, A. D. 1899.

HENRY ADLER.
